UNITED STATES PATENT OFFICE.

WILLIAM H. HART AND THOMAS CORSCADEN, OF NEW BRITAIN, CONNECTICUT, ASSIGNORS TO THE STANLEY WORKS, OF SAME PLACE.

DESIGN FOR A HINGE.

SPECIFICATION forming part of Design No. 18,956, dated March 12, 1889.

Application filed January 26, 1889. Serial No. 297,687. Term of patent 14 years.

To all whom it may concern:

Be it known that we, WILLIAM H. HART and THOMAS CORSCADEN, both citizens of the United States, residing at New Britain, in the county of Hartford and State of Connecticut, have invented and produced a new and original Design for a Hinge, of which the following is a specification, reference being had to the accompanying drawings, forming part thereof.

Figure 1 is an elevation of the outer side of a hinge, showing our design. Fig. 2 is a plan view thereof, and Fig. 3 is an elevation of the inner side of said hinge.

15 The leading feature of our design consists in a series of raised beads extending transversely around the knuckle and partially across each leaf.

20 A designates the two leaves of the hinge. B designates the knuckle thereof, and C C ornamental tips at the respective ends of said knuckle. The tips are only shown to make the hinge look more complete, as ornamented tips will ordinarily be employed in connection with a hinge of our design. The general form of the leaves and knuckle is of an ordinary character. The knuckle B is provided with a series of beads, 5, extending around it transversely. Upon that portion of each 25 hinge-leaf which is nearest the knuckle we arrange a series of beads, 4, which extend transversely across those portions of the hinge-leaves to the knuckle, and in effect form a

continuation of the beads 5, thereby giving the hinge the appearance of having a single 35 series of beads extending transversely around the knuckle and partially across the adjoining portions of each of the hinge-leaves, as shown.

Although the above is the effect of our design, in fact only a portion of the beads 4 are a continuation of the beads 5 around the knuckle. For example, take the leaf shown on the right-hand side of Fig. 1. The two upper and two lower beads of the beads 4 on said leaf are a continuation of the beads 5 on the knuckle, while the four beads 4 in the middle portion of the same leaf necessarily terminate at the side of the knuckle, as that is the termination of that portion of said leaf. 40 They are, however, in alignment with the beads 5 on the adjacent portion of the knuckle, so as to give the continuous effect before mentioned.

45 What we claim is—
50 The design for a hinge herein shown and described, the same comprising the leaves A A, knuckle B, and the series of beads 4 and 5, extending transversely around the knuckle and over the adjoining portions of both leaves. 55

WM. H. HART.
THOMAS CORSCADEN.
